UNITED STATES PATENT OFFICE.

EDGAR T. BOND, OF CHICAGO, ILLINOIS.

FOLDABLE CRATE.

1,085,590.

Specification of Letters Patent.

Patented Feb. 3, 1914.

Original application filed September 10, 1909, Serial No. 517,011. Divided and this application filed October 19, 1910, Serial No. 587,843.

To all whom it may concern:

Be it known that I, EDGAR T. BOND, a citizen of the United States, residing at Chicago, in the county of Cook and State of Illinois, have invented certain new and useful Improvements in Foldable Crates, of which the following is a specification, reference being had to the accompanying drawings, forming a part hereof, the same being a division of application Serial No. 517,011, filed September 10, 1909, by me.

This invention relates to foldable crates or receptacles designed more especially for transportation and storage purposes, but which are adapted for use and can be used for other purposes.

The objects of the invention are: to construct a crate or receptacle that will be light and easily handled, and at the same time will be strong and durable in use; to enable the crate or receptacle to be unfolded or set up for use without trouble or inconvenience, and to be quickly and readily folded together so as to occupy but a small space as compared with its unfolded or set-up condition; to form the sides and top of the crate or receptacle of strands or bars made of wire or strips of metal or other material of sufficient rigidity to furnish the necessary strength for the crate or receptacle when unfolded or set up; to form two opposite sides of a crate or receptacle of foldable companion sections, each section consisting of a support and crossbars or strands, and to form the remaining two sides of the crate or receptacle of standards or frames centrally hinged so as to fold inward and united in a flexible manner to the top and bottom of the crate; to form the four sides of the crate or receptacle of inwardly foldable standards or uprights centrally hinged and flexibly attached at the top and bottom to the top and bottom of the crate or receptacle; and to improve generally the construction and arrangement of the several parts entering into the formation of the crate or receptacle as a whole.

The invention consists in the features of construction and combinations of parts hereinafter described and claimed.

In the drawings Figure 1 is a side elevation showing a construction of foldable crate or receptacle having centrally hinged and foldable corner posts or standards and foldable frames located within the corner posts or standards, both the corner posts or stand-

ards and the frames carrying cross rods or strands for the sides of the crate or receptacle; Fig. 2, an elevation of the crate or receptacle shown in Fig. 1, with the parts partly folded; Fig. 3, a detail in elevation, 60 showing a portion of a crate or receptacle formed on the general plan of the crate or receptacle of Fig. 1, with a modification in the locking means for the swinging bars or frames within the corner posts or standards; Fig. 4, an elevation showing the construction of Fig. 3 partly folded; Fig. 5, a side elevation showing a modification in the attachment or hinging of the corner posts to the top and bottom of the crate or receptacle; 70 and Fig. 6, a detail in perspective of the connection or hinging means shown in Fig. 5.

The crate of the present invention has end or side strips or pieces 1 supporting a bottom 2 of any suitable construction and made of wood or other suitable material. At each corner of the crate is a standard or post formed of a lower section or member 3 and an upper section or member 4, with the two members centrally united by a suitable hinge 5 so as to fold inward. The bottom or lower end of each corner post, in the construction shown in Figs. 1, 2, 3 and 4, is flexibly united to the bottom of the crate or receptacle by a connection in the form of a coil spring. A 80 trunnion or bearing 6 is formed on the bottom and is encircled by the coil 7 of the spring connection, and, as shown, the ends 8 of the wire forming the coil spring are attached to the lower end of the standard or 90 post by staples 9, or in any other suitable manner. At each corner of the crate or receptacle, and within the corner posts or standards, is a support consisting of a lower member or section 10 and an upper member or section 11, foldably connected together at their adjacent ends as hereinafter described. The two opposite sides of the crate or receptacle are formed by cross rods or strands 12, united to the divided corner posts or 100 standards by having their ends entered into the corner posts or standards, as shown by dotted lines in Figs. 1, 2, 3 and 4, and by the circles in Fig. 5, thus bringing the bodies of the strands wholly within the edge plane of the corner posts or standards and leaving no projecting surfaces in the sides of the posts or standards; but the strands could be attached in any similar suitable manner. The 105 foldable connection between the two mem- 110

bers 10 and 11 of the supplementary frame or support, in the construction shown in Figs. 1 and 2, is formed by a socket 13 on the end of the upper member or section 11, which socket has an ear 14, which enters between ears 15 on the upper end of the lower member 10, and the ears are united by means of a pivot 16 so as to allow the two members or sections to fold inward at the connecting point, as shown in Fig. 2. The pivot 16 is off-center in its relation to the sections of the divided support, so that when the support is vertical, the pivot and ears 14 furnish a locking means for holding the divided support vertical or upright.

The lower end of the member or rod 10 and the upper end of the member or rod 11 have an eye 17, by means of which, and a staple 18 or other suitable means, the ends 20 of the divided support 10 and 11 are flexibly united respectively to the bottom and top of the crate or receptacle as shown in Figs. 1 and 2, so as to permit of the inward folding of the supplemental support. The remaining sides of the crate or receptacle are each formed by means of cross rods or strands 19, secured to the members of the supplemental support by staples 20 or in any other suitable manner, so that when the 30 crate is in its elevated or unfolded position, as shown in Fig. 1, it will have four sides formed by rods or strands supported by the corner posts or standards and by the supplemental supports, as shown in Fig. 1.

35 The top of the crate, in the construction shown, is formed by side strips 21, of wood or other suitable material, and cross-rods 22 united to the cross strips by staples 23, or in any other suitable manner. The upper 40 end of each member or section 4 of the divided corner posts or standards, as shown in Figs. 1, 2, 3 and 4, is flexibly attached to the rails or strips of the top or cover by means of a trunnion 6, a coil spring 7 with 45 the ends 8 of the coil wire attached to the post or standard by staples 9 or otherwise, in the same manner as the lower end of each divided standard or post is flexibly attached to the bottom of the crate or receptacle. The divided standards or posts, each united at the top and bottom by a flexible connection furnished by the coil spring, allow of the requisite yield in the 50 central folding and unfolding of the posts or standards in raising the crate or placing the crate in a folded condition.

The construction shown in Figs. 3 and 4 employs the corner foldable standards or posts and the supplemental support of the 55 crate of Figs. 1 and 2, but the supplemental support is operated in a slightly different manner, as to the locking means for holding the two members or sections of the support in the elevated position. The two members 60 or sections of the supplemental support are

flexibly united respectively to the top and bottom of the crate or receptacle by means of a coil 24, one end 25 of the wire of the coil being inserted and fastened in the bottom and top strip of the crate or receptacle 70 and the other end 26 of the wire coil being united to the end of the section of the divided support by staples 27 or otherwise, as shown in Figs. 3 and 4. The coil or spring connection 24 furnishes a flexible connection for the divided supplemental support, the same as the springs 7 furnish a flexible connection for the corner standards or posts, so that the two members or parts 10 and 11 of the supplemental support can fold with 80 the folding of the crate or receptacle, as shown in Fig. 4.

The upper end of the lower frame or member 10 of the supplemental support, as shown in Figs. 3 and 4 is encircled by an 85 eye 28 on the end of a rod 29, the other end of which has an eye 30 through which passes a pivot pin 31 uniting the rod 29 to an ear 32 on a socket 33 mounted on a sliding rod 34 slidably mounted on the bottom 90 of the crate or receptacle, and held in position by staples or eyes 35 or in any other suitable manner, so as to be free to slide longitudinally. The lower end of the upper frame or member 11 of the supplemental 95 support, as shown in Figs. 3 and 4, is encircled by an eye 36 on a rod 37, the other end of which has an eye 38 through which passes a pin or pivot 39 uniting the rod to an ear 40 on a suitable socket 41 fixedly 100 mounted on a sliding rod 42, which is movably held in place by links or eyes 43 encircling a rod 44 attached to the frame strips of the top or cover of the crate, as shown in Figs. 3 and 4.

105 The two members 10 and 11 of the divided frame or support of Figs. 3 and 4 swing inward from their flexible connection at the top and bottom when the crate is folded, and swing outward from the spring connection when the crate is unfolded. The central inward swing of the members of the divided frame or support is permitted by rods 29 and 37, and the sliding connection for these rods with the bottom and top 110 of the crate or receptacle. The sliding connection is also one which, when the crate is raised or unfolded, furnishes a lock for the entire crate against collapsing or falling down with ordinary usage, as the bind 115 between the sliding rods 34 and 43 and the supports for these rods is sufficient to furnish a lock against the inward swing of the divided frame or support at the center, holding the divided frame or support in its vertical position and sustaining the crate or receptacle in its elevated or unfolded shape.

120 The construction of the crate or receptacle of the present invention is one which permits the crate or receptacle to be unfolded 125

and folded by raising and lowering the corner posts or standards, which fold centrally inward, and at the same time the divided supplemental support is free to swing inward on its pivotal connection or on the sliding rods or braces, so that the strands or wires forming the sides of the crate or receptacle are carried downward in the folding operation as shown in Figs. 2 and 4, and are carried upward in the unfolding operation as shown in Figs. 1 and 3. The crate or receptacle is one which can be readily handled in unfolding and folding, and at the same time the construction is of a nature to furnish a strong crate or receptacle and one which is exceedingly light and easily handled.

The divided corner posts or standards, instead of being connected at the upper and lower end by a flexible spring connection, can be attached to the rails of the bottom and top of the crate by means of staples or eyes 45 driven into the ends of the divided posts or standards, and entered in staples or eyes 46 driven into the rails of the top and bottom, as shown in Figs. 5 and 6; and under the term "flexible" is included a coil or loop connection which will permit a yield or play that will allow of a folding of the posts and supports at their top and bottom connections.

It is to be noted that the construction and arrangement of the sides of the crate or receptacle of the present invention is one in which all four sides are supported by foldable members, so that the supporting members can swing inward, carrying with them the strands or strips forming the four sides of the crate or receptacle; and it is evident that the strands could be made of wire or strips of metal or other material of a nature to allow of the folding and unfolding of the sides of the crate or receptacle by lowering and raising the divided corner posts or standards and the divided supplemental frames or supports.

The advantages pertaining to the crate or receptacle of the present invention are apparent, and need not be described in detail. Suffice it to say that the crate can be readily and quickly unfolded and folded, is very strong and durable, and at the same time light and easily handled; and when folded can be stored away and occupy but a small space in a room or other storing place.

It is not the intention to limit, restrict, restrain, or confine the mechanism in these devices for use in foldable crates, and under the word "crate" is included coops for chickens, crates for the transportation of berries, vegetables or other commodities, receptacles, carrying cases for eggs, folding boxes, cases or crates for the delivery of packages or bundles commonly put up in grocery stores, meat markets and other retail

stores in any general merchandise line of business, for commercial use in delivery of packages to customers, patrons and consumers.

The foldable crate or receptacle of the present invention has two opposite sides centrally and inwardly foldable crosswise of the crate or receptacle, and the two remaining opposite sides centrally and inwardly foldable lengthwise of the crate or receptacle. Two of the opposite sides consist of divided corner posts or standards suitably hinged together so as to fold inwardly at the center, and connected at the top and bottom by a spring or other form of loose hinge to the bottom and top of the crate or receptacle. The two remaining sides of the crate or receptacle consist of a divided supplemental support for each side, either with or without bracing means for each member or section of the support. The crate is completed by means of strands connected to the divided posts or standards and to the divided supplemental frame or support, and under the term "strand" is included a wire, a small-sized rod, a strip, a small bar, or a twisted strand or other form of connecting means; and it is to be understood that the strand can be of various shapes in cross-section, such as round, oval, square, rectangular, triangular, or other shape.

The gist of the present invention is in constructing the crate or receptacle with all four of its sides centrally and inwardly foldable, two of the sides foldable in the opposite direction to the folding of the other two sides, and having all four sides completed by means of strands, thereby furnishing a crate which will be light, strong and durable, and which can be folded in a compact shape when not in use.

What I claim as new and desire to secure by Letters Patent is:

1. In a foldable crate, the combination of a bottom, a top, four corner posts, one post for each corner of the crate, each post consisting of two sections jointed at the center one to the other and adapted to fold centrally and inwardly, each post also inwardly foldable from its lower end, a series of spaced apart cross-strands carried by each two of the divided corner posts, with the ends of the strands entered into the posts and the strands located within the edge plane of the posts, four divided supports, one support adjacent to each corner post, each support centrally and inwardly foldable at the division line and each support also inward foldable from its lower end, the folding of the supports being at right angles to the folding of the corner posts, and a series of spaced apart cross-strands carried by each two of the divided supports, the cross-strands of the supports running at right angles to the cross-strands of the posts and

the four corner posts, the four supports and the four series of cross-strands forming the four sides of the crate, substantially as described.

- 5 2. In a foldable crate, the combination of a bottom, a top, four corner posts, one post for each corner of the crate, each post divided midway of its length and provided at the division line with a hinged connection 10 for the post to fold centrally inward, a yieldable connection for each post with the bottom of the crate for the post to fold inwardly from its lower end, a series of spaced apart cross-strands carried by each 15 two of the divided corner posts, with the ends of the strands entered into the posts and the strands located within the edge plane of the posts, the four divided corner posts and the two series of cross-strands 20 forming two opposite foldable sides of the crate, four divided supports, each support flexibly connected at its upper end with the top of the crate and each support flexibly connected at its lower end with the bottom 25 of the crate, and adapted to fold centrally inward between its top and bottom connections, the folding of the supports being at right angles to the folding of the corner posts, and a series of spaced apart cross- 30 strands carried by each two of the divided supports, the two series of cross-strands and the four divided supports forming the other two opposite foldable sides of the crate, substantially as described.
- 35 3. In a foldable crate, the combination of a bottom, a top, four corner posts, one post for each corner of the crate, each post divided midway of its length and provided at the division line with a hinged connection 40 for the post to fold centrally inward, a coil spring connecting each post at its upper end with the top of the crate, a coil spring connecting each post at its lower end with the bottom of the crate, the coil springs per- 45 mitting each divided post to inwardly fold between the bottom and top of the crate, a series of cross-strands spaced apart and carried by each two of the divided corner posts, with the ends of the strands entered into the 50 posts and the strands located within the edge plane of the posts, the four divided corner posts and the two series of cross-strands forming two opposite foldable sides of the crate, four divided supports, one sup- 55 port located adjacent to each corner post, a coil spring connecting each divided support at its upper end with the top of the crate, a coil spring connecting each divided support at its lower end with the bottom of the crate, 60 the coil springs permitting each divided support to fold inwardly between the top and bottom of the crate, and in a direction at right angles to the inward folding of the corner posts, a series of cross-strands spaced

apart and carried by each two of the divided 65 supports, the two series of cross-strands and the four divided supports forming the other two opposite sides of the crate, substantially as described.

4. In a foldable crate, the combination 70 of a bottom, a top, two opposite sides of the crate, each side inwardly and downwardly foldable, four corner posts, one post for each corner of the crate, each post divided midway of its length and provided at the division 75 line with a hinged connection for the post to fold centrally inward, a flexible connection for each post at its upper end with the top of the crate, a flexible connection for each post at its lower end with the 80 bottom of the crate, the flexible connections permitting each divided post to inwardly fold between the top and bottom of the crate, and a series of cross-strands spaced apart and carried by each two of the divided 85 corner posts, the four divided corner posts and the two series of cross-strands forming two remaining opposite foldable sides of the crate, substantially as described.

5. In a foldable crate, the combination of 90 a bottom, a top, two opposite sides of the crate, each side inwardly and downwardly foldable, four divided supports, one support located adjacent to each corner of the crate, each divided support connected at its ad- 95 joining ends to fold centrally inward, a flexible connection for each divided support at its upper end with the top of the crate, a flexible connection for each divided support at its lower end with the bottom 100 of the crate, the flexible connection permitting each divided support to fold inwardly between the top and bottom of the crate, and a series of cross-strands spaced apart and carried by each two of the divided supports, the four divided supports and the two series of cross-strands forming two remaining op- 105 posite foldable sides of the crate, substan- tially as described.

6. In a foldable crate, the combination of 110 a bottom, a top, four divided corner posts, one for each corner of the crate, a series of spaced-apart cross strands for each two of the divided corner posts, four divided supports, one support located adjacent to 115 each corner of the crate, and outside of the cross strands of the corner posts, each di- 120 vided support adapted to fold centrally in- ward, a connection for each divided support at its upper end with the top of the crate, a connection for each divided support at its lower end with the bottom of the crate, the connections permitting each divided sup- 125 port to fold inwardly between the top and bottom of the crate, and a series of cross- strands spaced apart and carried by each two of the divided supports, the four divided corner posts, the four divided sup-

ports and the four series of cross-strands forming the four foldable sides of the crate, substantially as described.

7. In a foldable crate, the combination of 5 a bottom, a top, four divided corner posts, one for each corner of the crate, four divided corner supports, each yieldably connected at its upper and lower end with the top and bottom of the crate, and each adapt-

ed to fold centrally inward, and means for 10 locking the supports and maintaining the supports and posts in their vertical position, substantially as described.
